FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,282,823.

Specification of Letters Patent.

Patented Oct. 29, 1918.

Application filed February 23, 1916. Serial No. 79,969.

To all whom it may concern:

Be it known that I, FREDERICK A. HART, a citizen of the United States, residing in Newark, in the county of Essex and State 5 of New Jersey, have invented certain new and useful Improvements in Combined Type-Writing and Computing Machines, of which the following is a specification.

This invention relates to computing machines, and is herein disclosed as applied to 10 a combined typewriting and computing machine of the type shown in the patent to Hanson, 816,319, patented March 27, 1906, and in my Patent 1,188,933, patented June 15 27, 1916.

In such machines it has been found advantageous to provide connections such that the pointing off between the figures, as between dollars and cents, and between hundreds and thousands, etc., may be done in 20 the regular course of writing numbers. The actual pointing off, however, involves the operation of comma or period keys at intervals during the writing of numbers, and 25 consequently the depression of said comma and period keys is likely to be overlooked or to be effected at the wrong place. In the writing, however, of printed numbers such as a typewriter prints, the mechanical 30 connections automatically effect the printing of such numbers in vertical lines, irrespective of printing in the pointing off spacings, and in actual practice it is found that the 35 printing in of commas and periods is unnecessary in most of the work for which such computing machines are used, just as such pointing off is unnecessary in ordinary bookkeeping in which the bookkeeper keeps the decimal position of the digits by writing 40 said digits between ruled lines, and as a matter of practice, usually omits commas and periods.

The present invention is adapted to relieve the operative of the necessity of printing 45 said commas and periods, and at the same time provide automatically for whatever spacing may be desired, without compelling the operative to effect said spacing either by the operation of a printing key or 50 the operation of a space bar. To do this, I have found it advantageous to modify the escapement mechanism and provide for a double letter-feeding of the typewriter carriage in printing the digit immediately to 55 the left hand of the pointing-off space. I

have found it possible to do this in such a manner that the speed of operation of the machine need not be reduced at all, and to accomplish this effectively I have found it advantageous to provide an escapement in 60 which the usual loose and fixed typewriter escapement dogs are provided, but I have found it possible to introduce means whereby, in the proper letter spaces in the computing zone, the loose dog of the typewriter 65 will selectively have sufficient additional throw to feed the typewriter carriage the required two letter spaces at a single operation, and yet always have the positive control of the typewriter carriage usual in the 70 Underwood escapement. This produces a simple mechanism which is not likely to get out of order and if abused and broken is easily cared for by any typewriter repair man. To control this selective feeding of 75 the loose dog of the typewriter, I have found it advantageous to provide a member adjacent some denominational selecting device connected with the computing mechanism in such a way that at the proper 80 pointing-off places said denomination-selecting device will cause said member to modify the action of the loose dog of the typewriter. In the Underwood-Hanson machine I have found it advantageous to utilize the column 85 stop which is usually placed to correspond to the denomination selecting dog for operating said member. In order to enable this column stop to effect such an operation while at the same time providing that other 90 column stops shall not be effected thus, a tail may be provided on the column stop which is to control the typewriter loose dog, 95 said tail being absent from the other column stops.

In order to decrease the number of possibilities of error by the operative, I have found it advantageous to provide that the typewriter carriage shall be arrested by the decimal tabulating mechanism only at denominations where numbers are to be written in, and to obtain this result I have found it merely necessary to omit certain of the usual Underwood decimal stop plungers. This last modification applies primarily to machines in which the same kind of computation is done in every computing zone; and in some cases, as where a machine is used for computing on one register in dollars and cents, and another in units, tens, hun- 105 110

dreds and thousands only, such modification of the decimal tabulator mechanism may be found inadvisable.

Other features and advantages will herein-
5 after appear.

In the accompanying drawings,

Figure 1 is a transverse vertical section of the machine, some of the parts being broken away and others omitted.

10 Fig. 2 is a detail front elevation of the upper portion of the tabulator stop bracket, showing part of the means for skipping a space.

Fig. 3 is a skeleton perspective view, show-
15 ing the toothed bail connected to a shiftable stop member with which a loose dog of the escapement coöperates at different times for effecting a single or double space movement of the typewriter carriage.

20 Fig. 4 is a detail front elevation showing the arrangement and spacing of the selecting jacks and their corresponding thrust rod.

Fig. 5 shows the arrangement and spacing
25 of the register wheels as seen through the sight opening.

Fig. 6 is a fragmentary front elevation of the typewriter escapement and shows the parts set for single letter spacing.

30 Fig. 7 is a similar view with the escapement dogs rocked rearwardly.

Fig. 8 is similar to Fig. 7, except that the escapement is set for double space.

Fig. 9 is a detail sectional plan view taken
35 on the line 9—9 of Fig. 6, and shows the mounting for the shiftable stop member of the escapement.

The typewriting machine is of the usual
40 Underwood construction, in which numeral
keys 21 and alphabet keys 22, when de-
pressed, cause key levers 23 to swing about
the fulcrum 24, rocking the bell crank le-
vers 25, to swing the type-bars 27 pivoted
45 at 28 upwardly and rearwardly causing the
types 29 to print against a cylindrical platen
30, rotatably mounted on the typewriter car-
riage 31.

The typewriter carriage 31 is under con-
stant tension of a spring drum 32 which
50 tends to move the carriage from right to
left. For feeding the typewriter carriage
letter-space distances, it is provided with
a rack 34 which meshes with the pinion 35
to rotate an escapement wheel 36 connected
55 to said escapement wheel by the usual pawl.
This escapement wheel coöperates with a
loose dog 38 and a fixed dog 37 mounted on
the dog carrying frame or rocker 39.

The typewriter escapement, except the
60 double spacing feature herein described, is
in many respects like that disclosed in Pat-
ent 769,804, to Rice, *et al.*, and operates in
the following manner:

Heels 40 on type-bars 27, as the type-bars
65 rise, strike a curved universal bar 42 press-

ing it back against the tension of the usual
spring 42^a to rock the dog rocker 39 rear-
wardly against the tension of a spring 43,
moving the fixed dog 37 into the path of the
teeth 44 of the escapement wheel 36, and
70 releasing said escapement wheel from the
loose dog 38. The loose dog 38 immediately
swings past the tooth 44 under the influence
of the spring 43 against a lug 45 of the stop
member 46. The escapement mechanism is
75 brought back to normal position, as indi-
cated in Fig. 6, on the down stroke of the
type-bars. To do this, the spring 43 moves
the fixed dog 37, clear of the escapement
wheel, thus allowing the adjacent tooth 44
80 of the escapement wheel to engage with the
loose dog 38, with the result that the tension
of the carriage spring causes the escapement
wheel to carry the loose dog back to nor-
mal position against the fixed stop 47 on the
85 dog rocker 39, so that the said loose dog
again holds the typewriter carriage.

The stop member 46 is pivotally mounted
on a stud 49 rigidly secured to the escape-
ment bracket and held thereon by nuts 50.
90

To effect the double space movements at
predetermined positions of the typewriter
carriage, I have provided means for shifting
the stop member 46, so as to vary the throw
of the loose dog 38. In order to vary the
throw of the loose dog 38, the edge of the
stop member 46 is turned up at one point
to form a second extra feed lug or stop 54,
and when this lug 54 is in effective position
the freeing of the loose dog on the rearward
movement of the universal bar will cause the
dog to be drawn back by its spring 43 to the
next tooth 44 but one of the escapement
wheel 36, with the result that the return
or forward stroke of the universal bar 42
100 and dog rocker 39 will feed the carriage
two letter-spaces, because the escapement
wheel will carry the loose dog 38 along two
teeth before being arrested thereby.

This shifting of the stop member 46 is
brought about by a bail 51 which is car-
ried on pivot screws 52 and is connected by
a link 53 to bring the stop 54 into position to
permit this extra drawing back of the loose
dog 38. Said bail is provided with cams 55,
115 which are engaged by the extra long tail 56^a
of the tabulator stop 56, when the carriage
moves transversely of the machine, said
stop being mounted as usual on a stop bar
57 carried by the typewriter carriage.

The cams 55 are set at distances apart cor-
responding to the letter-spaces used for
pointing off between numbers with the re-
sult that in writing numbers the typewriter
carriage will automatically jump across the
pointing-off spaces, even though the nu-
meral keys are depressed as if to write the
number without pointing off,—it being as-
sumed that the tabulating stop is properly
positioned. Thus after writing in the tens
125

of thousands position of the number being written, the carriage with its tabulator stop advances a letter-space distance to thousands position and engages with one of the 5 cams or tappets 55 on the bail 51, thus swinging the latter to shift the stop-carrying member 46 to bring the extra feed lug 54 into active position, so that while the escapement dogs at this time have the position 10 shown in Fig. 6, the stop-carrying member 46 is in the position shown in Fig. 8.

The next digit is the one written in thousands column. When the type-bar is swung up to print in the thousands position, the 15 dog rocker 39 is rocked, causing the loose dog 38 to become disengaged from the escapement wheel, and allowing it to be moved back the space of two escapement wheel teeth to the position shown in Fig. 8 under 20 the influence of its spring 43, where it is arrested by the stop 54. On the return stroke of the type-bar, when the dog rocker comes back to normal position, the loose dog 38 will be brought into the path of the adjoining oncoming tooth of the escapement 25 wheel, viz., one tooth farther back than normal. This tooth carries the dog back to normal position against the fixed stop 47 of the dog-carrying member, and owing to the 30 fact that the dog started one tooth farther back than normal, the escapement wheel is only arrested by the dog after traveling one tooth farther than normal; in other words, the carriage is fed an extra letter-space.

35 The loose dog 38 is provided with a notch 59, to provide for the free movement of the dog which otherwise might strike the side of the intervening tooth 44 on the escapement wheel when the dog rocker 39 is returning to normal position, in giving the 40 carriage the double letter feed shown in Fig. 8.

To return the bail 51 and dog 41 to normal position, there is a spring 60 coiled 45 about one of the pivot screws 52, one end being fastened to the bail 51, and the other end being held by a bracket 61 to which said bail is pivoted.

The bracket 61 is adjustably mounted on 50 threaded rods fast on the tabulator plunger bracket 63, for the purpose of adjusting the cams 55, so that they coöperate with the tabulator stop at the proper time during the travel of the typewriter carriage. After 55 said cams have been properly adjusted, the bracket 61 is permanently secured to the tabulator plunger bracket by means of lock nuts 64 and 65.

The tabulator is of the regular Underwood construction in which the depression of any key 70 swings its lever 71 to move the upper end of its plunger 72 into the path of the tabulator stop 56 on the typewriter carriage, said typewriter carriage being released in the regular way by the plunger 72,

causing the short universal bar 73 to swing about a pivot 74 and rock the carriage release lever 75 which by the usual roll lifts the rack bar 34 pivoted to the typewriter carriage, the link 76 forming a connection 70 between the universal bar 73 and the release lever 75.

For the purpose of making the computing mechanism effective when the typewriter carriage reaches a computing zone, there 75 is mounted on the typewriter carriage the usual adjustable denomination selecting tappet 81 which rocks a series of jacks 82, one at a time, to move a thrust rod 83 downwardly, which swings a bell crank 84 about 80 a fulcrum 85, causing one of the linkages 86 to raise one of the computing bars 87, so that the pins 88 are brought into coöperative relation with the linkages 89.

To set a pin 88 on the computing slide 85 after it has been raised, there is a stem 90 on each number key 21 which, when depressed, rocks a shaft 91 by means of a rock arm 92, thus causing the corresponding linkage 89 to depress one of the pins 88, so that the lower 90 end thereof will enable its computation bar to be driven at the proper time by the horizontal bar 93, forming part of the general operator 94.

The computation is then completed on the 95 computing wheels 98, substantially in the manner described in the said Hanson Patent 816,319, patented March 27, 1906.

The stop member 46, it will be observed, is provided with a long extension 99 forming 100 a journal which encircles a long stub shaft projecting from the bracket on which the dog rocker is journaled, thus forming an adequate bearing for the stop member 46 on which it is held by the end locked nuts 105 100. The link 53 is connected to an arm 101 of said stop member which lies close to said bracket, and the stops 45 and 54 of said member are connected to the journal extension by a double elbow 102.

By an inspection of Fig. 3 it will be seen that certain tabulator plungers, ordinarily used for punctuation positioning in a column of numbers, are omitted, so that there is only one tabulator key for cents, 115 since units of cents are always written with a zero in the tens place. The operative is therefore unable to arrest the typewriter carriage at a point where it is improper to write a number.

The jacks 84 and their respective thrust rods 83 are omitted at punctuation points as shown in Fig. 4, so as to make effective the pin setting only when a denominational position in a column of figures is reached. 125 The register or computing wheels 98 are equally spaced with relation to each other, as shown in Fig. 5. Thus my invention provides means whereby registers of uniform construction may be utilized for com- 130

puting numbers however pointed off, and since the jacks 82 may be shifted to the punctuation points, and the rods 83 variably adjusted as described in my aforesaid 5 patent by the simple expedient of inserting a new bail 57, I can alter the punctuation spacing in a machine without altering the register, while at all times the machine is an ordinary typewriting machine outside 10 of a computing zone. Tabulating stops of the ordinary kind may be employed for locating the carriage outside of the computing zone, these stops being substantially identical with the stop 56 but lacking the 15 tail, or the stop 56 may be provided with a tail on one prong only, with the result that said stop may be utilized either in typewriting only, or for computing purposes, by merely inverting it.

20 In order to provide for the proper arresting of the typewriter carriage in a tabulating operation, the stop 45 is out of the path of the loose dog 38 unless said dog is rocked back by the dog rocker, but turned up edge 25 54 of the dog stop is long enough to always lie in the path of the pin 54^a on the loose dog 38, with the result that when the carriage is released from the escapement mechanism by depressing a tabulator key, the 30 loose dog is drawn by its spring so that it turns the escapement wheel back two teeth, viz., till the pin 54^a strikes the edge 54. Then on releasing the tabulation key, the loose dog receives the carriage from the 35 stop 56, and lets the carriage step forward about two letter spaces. This stepping forward is offset by positioning the tabulator stop 56 properly on the carriage relatively to the plungers 72. In practice this may be 40 conveniently done by adjusting the scale used for locating the column stops 56, so that the final position of the carriage when released from its tabulator stop will agree with the proper position of the denomination 45 selector tappet 81 relatively to its scale, and with the usual front scale of the typewriter.

Variations may be resorted to within the scope of the invention, and portions of the 50 improvements may be used without others.

Having thus described my invention, I claim:

1. In a combined typewriting and computing machine, the combination with a 55 totalizer having equally-spaced wheels, of type-writing mechanism including a traveling typewriter carriage for determining how numbers shall be printed by said type-writing mechanism, means for causing said 60 carriage to select the wheels in which computation shall be effected, and means for causing said carriage at predetermined letter-spaces to make a two-letter-space movement to represent a punctuation space in a 65 computation, the connections being such

that said carriage in making said two-letter-space movement selects the wheel adjacent to the one just previously selected.

2. In a combined typewriting and computing machine, the combination with computing mechanism, of a typewriter carriage, a denomination selector for said mechanism settable on said carriage, typewriter printing keys adapted to compute in said mechanism, reciprocating escapement devices operated by said keys to cause the carriage to feed letter-space distances, and means adapted to be set on said typewriter carriage in alignment with the denomination selector to cause said escapement devices to feed said carriage two-letter spaces at a single operation of one of said keys. 70 75

3. In a combined typewriting and computing machine, the combination with computing mechanism, of a typewriter carriage, 85 a denomination selector for said mechanism settable on said carriage, typewriter printing keys adapted to compute in said mechanism, reciprocating escapement devices operated by said keys to cause the carriage to feed letter-space distances, and a tabulator stop adapted to be set in alignment with said selector for positioning said carriage, said stop including means for causing said typewriter carriage to be fed two letter- 90 95 spaces by said escapement devices at a single operation of one of said keys.

4. In a combined typewriting and computing machine, the combination with computing mechanism including a denomination selector and computing wheels, of a typewriter carriage for causing said selector to be effective to select said wheels, a tabulating stop adapted to be positioned to bring said carriage to rest at a point where 100 said selector will be effective to select said wheels, typewriter printing keys adapted to compute in said mechanism in denominations selected by said selector, reciprocating escapement devices operated by said keys to 105 cause the carriage to feed letter-space distances, connections from said escapement devices, and an extension of said stop adapted to operate said connections, to cause said escapement devices to feed said carriage 110 two letter-spaces at a single operation of one of said keys. 115

5. In a combined typewriting and computing machine, the combination with computing wheels and a typewriter carriage, 120 of connections including unequally-spaced jacks, whereby said carriage is adapted to select said wheels, a denomination selector carried by said carriage for operating said jacks to effect said selection, typewriter numeral keys adapted to determine how far said computing wheels shall turn, and connections, whereby said keys cause said carriage to select adjacent jacks at any operation of said keys. 125 130

6. In a combined typewriting and computing machine, the combination with computing wheels and numeral keys, of a typewriter carriage, a denominational selector for said wheels settable on said carriage, jacks on which said selector is effective to select said wheels, certain of said jacks being at the normal spacing of one letter-space apart, others being two letter-spaces apart, escapement devices for said carriage adapted to normally feed said carriage one letter-space at each depression of a numeral key between normally-spaced jacks, and connections whereby said carriage is fed by said escapement devices two steps at a time between jacks spaced two spaces apart. 65
7. In a combined typewriting and computing machine, the combination with computing wheels and numeral keys, of a typewriter carriage, a denomination selector for said wheels settable on said carriage, spaced jacks on which said selector is effective to select said wheels, certain jacks being spaced two letter-spaces apart, others being spaced the normal one letter-space apart, escapement devices for said carriage adapted to normally feed said carriage one letter-space at each depression of a numeral key, a tabulating stop adapted to be set on said carriage in alinement with said denomination selector, and connections whereby said stop is adapted to control said escapement devices, to cause said devices to feed said carriage two letter-spaces between jacks spaced two letter-spaces apart, and permit said carriage to feed single letter-spaces between normally-spaced jacks. 70
8. In a combined typewriting and computing machine, the combination with computing wheels, of a typewriter carriage, a denomination selector for said wheels settable on said carriage, spaced jacks on which said selector is effective to select said wheels, certain jacks being spaced two letter-spaces apart, others being spaced the normal one letter-space apart, escapement devices for said carriage adapted to normally feed said carriage one letter-space at each depression of a numeral key, a tabulating stop settable on said carriage in alinement with said denominational selector, a bail adjacent the line of travel of said stop, tappets on said bail, and an extension on said stop adapted to operate said bail by said tappets, to cause said escapement devices to feed said carriage two letter-spaces, said tappets being so located that they cause the typewriter carriage to feed single letter-spaces between normally-spaced jacks, and double letter-spaces between said jacks spaced double letter-spaces apart. 75
9. In a combined typewriting and computing machine, the combination with a totalizer having equally-spaced wheels, of typewriting mechanism including a traveling typewriter carriage for determining where numbers shall be printed by said typewriting mechanism, means including jacks and a denomination selector for causing said carriage to select the wheels in which computation shall be effected, a tabulating stop for positioning said carriage, and means operated by said stop for causing said carriage at predetermined letter-spaces to make a two letter-space movement to represent a punctuation space in a computation, the connections between the jacks and wheels being such that said carriage in making a two letter-space movement selects the wheel adjacent to the one previously selected. 80
10. In a combined typewriting and computing machine, the combination with a traveling carriage and a denomination selector settable thereon, of equally-spaced computing wheels adapted to be selected by said selector, according to the position of said carriage, tabulating stops for positioning said carriage, unequally-spaced jacks whereby said selector selects said wheels, an escapement device for said carriage adapted to feed the carriage single letter-space intervals, a connection whereby said escapement device may feed the carriage two letter-space intervals, one of said tabulating stops in alinement with said selector, comprising a tail adapted to operate said last-named connection, to cause a two letter-space feeding, and another tabulating stop adapted to be set out of alinement with said selector and always ineffective on said last-named device. 85
